US00D516548S

(12) **United States Design Patent** (10) Patent No.: **US D516,548 S**
Corley et al. (45) Date of Patent: **** Mar. 7, 2006**

(54) **HANDHELD COMMUNICATION DEVICE**

D278,059 S 3/1985 Desrochers
D278,341 S 4/1985 Scheid

(75) Inventors: **Cortez Corley**, Waterloo (CA); **Roman Peter Rak**, Waterloo (CA)

(Continued)

(73) Assignee: **Research in Motion Limited** (CA)

(57) **CLAIM**

The ornamental design for a handheld communication device, as shown and described.

DESCRIPTION

FIG. 1 is a perspective view of a handheld communication device of our new design;

FIG. 2 is a front view thereof;

FIG. 3 is a top view thereof;

FIG. 4 is a bottom view thereof;

FIG. 5 is a left side view thereof; and,

FIG. 6 is a right side view thereof.

The broken line showings of FIGS. 1-6 are for illustrative purposes only and form no part of the claimed design.

1 Claim, 4 Drawing Sheets
